CLAIM

The ornamental design for a wrist watch, as shown and described.

DESCRIPTION

FIG. 1 is a front, right and top perspective view of a wrist watch, showing my new design;

FIG. 2 is a rear, left and bottom perspective view thereof;

FIG. 3 is a rear view thereof;

FIG. 4 is a front view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 of FIG. 1 thereof; and,

FIG. 10 is an enlarged view of portion 10 of FIG. 2 thereof. The dot-dash broken lines in FIGS. 1, 2, 9, and 10 are included to show a partially enlarged view only and form no part of the claimed design.

1 Claim, 10 Drawing Sheets
